APPARATUS FOR THE RECOVERY OF CHEMICALS FROM BLACK LIQUOR

Alexander L. Hamm, New York, N. Y., assignor to Combustion Engineering Company, Inc., New York, N. Y., a corporation of Delaware

Application October 19, 1940, Serial No. 361,874

5 Claims. (Cl. 122—235)

This invention relates to the recovery of chemical and the deriving of heat from the black liquor of wood pulp mills, and its nature, objects and advantages will be best understood from the following.

Briefly, the system ordinarily employed, comprises a smelter furnace and a waste heat boiler and its appurtenances. The black liquor, reduced to the desired density or concentration of solids, is introduced into the furnace, wherein it is evaporated to substantial dryness, the solid matter collected on the hearth of the smelter where reduction takes place. The chemical thus recovered runs off in molten state. Air is admitted to the fuel bed in an amount sufficient to maintain a reducing atmosphere. The combustibles in the gases rising from the fuel bed are burned, for which purpose additional air is admitted above the fuel bed. The smelter furnace is lined with steam generating tubes connected into the circulation of the waste heat boiler proper. Heat which would otherwise be lost is recovered in the generation of steam.

There is of course chemical in vaporized form in the fuel and flame stream and waste gases, mostly sublimed sodium sulphate and sodium carbonate. Due to the absorption of heat by the heat absorbing surface of the boiler unit, the vaporized chemical is condensed. The globules or particles of condensed chemical occasion difficulties in the banks of tubes of the boiler, particularly at the place where the gas stream in which they are carried enters the first boiler pass at right angles to the boiler tubes. The globules impinge upon, adhere to and build up on the tubes at such point and the solid deposit cannot be removed by soot blowers or hand lancing, but must be chipped off.

Attempts have been made heretofore to overcome this difficulty. One way employed has been to locate a number of tubes in advance of the boiler pass substantially at right angles to the line of gas flow, functioning after the fashion of the "slagging" tubes so frequently employed in advance of the boiler tubes in pulverized fuel burning equipment. While this arrangement reduces the amount of carry over into and minimizes difficulties in the boiler tube banks, it, in effect, only shifts the seat of the difficulty to the so-called slagging tubes, and it is still necessary to shut down the installation for removal of the deposit with suitable chipping tools.

It has also been proposed to minimize the difficulties by decreasing the amount of carry over of chemical into the boiler by cooling the globules

sufficiently to cause them to stick together as they contact with one another in space, thus causing them to agglomerate into larger particles which gravitate to the fuel bed. While this is an improvement upon the first way described, it is nevertheless still necessary from time to time to shut down for the removal of deposit (about every 6 or 7 weeks).

The chief object of this invention is to make it possible to operate substantially indefinitely without the need of shut-downs from the above cause.

I have discovered that the desired result is obtained if the gases are sufficiently cooled before entrance into the first boiler pass, provided that substantial impingement of the gases upon the surfaces employed for that purpose is avoided, and that this can be done economically and practically, and without interfering with self-sustaining operation of the unit. By cooling the gases and the entrained particles sufficiently, the particles do not stick to and build up upon the boiler tubes even at the point where the gases flow across the tubes at right angles and forcibly impinge. By avoiding substantial impingement of the gases and entrained particles upon the cooling surfaces employed for that purpose, even though the particles be molten, sticking and building up on said surfaces is avoided. All deposit on all surfaces is thus either powder or of a powdery and friable nature, such that the deposit can be easily removed from the surfaces by the use of soot blowers and hand lances, without the need of shut-down.

In the drawings:
Figure 1 is a more or less diagrammatic vertical section through a smelter and boiler for practicing the invention;

Figure 2 is a section taken on the line 2—2 of Figure 1, on an enlarged scale;

Figure 3 is a section taken on the line 3—3 of Figure 1, on an enlarged scale, and

Figure 4 is a section illustrating a modification of the water walls employed in carrying out the invention.

Referring now to Figure 1, the reference character A denotes the smelter furnace, the four walls of which are lined with exposed, one inch flinned, three inch tubes 7, spaced on five and one-half inch centers, connected with the boiler proper C for circulation, as will further appear. Immediately above the smelter furnace A is a chamber B to the rear of which is the boiler proper C, the appurtenances of which (such as economizer, air preheater and the like) are not

shown. The furnace chamber A and the chamber B are of substantially equal height, and have an overall height of sixty feet. The tubes 7 are approximately thirty feet long in the installation shown.

The black liquor evaporated to the desired density, approximately 65% to 70% solids, is introduced into the furnace chamber by the nozzles 8, the black liquor being supplied to the nozzles at a pressure from about 75 to 100 pounds per square inch and at a temperature of from 230° to 240° F., as described in U. S. Letters Patent No. 2,213,052, issued August 27, 1940. Owing to the reduction in pressure at the spray nozzles, some of the moisture contained in the sprayed particles flashes into steam, thus further increasing the density of the particles. The sprayed particles gravitate in counterflow with the rising flame and gas stream from the smelting zone and are dried in space to substantial dryness. The dried particles collect on the hearth in the form of a bed of fuel 9. Preheated air for reduction is admitted through the fuel bed by means of the air nozzles 10, in an amount sufficient to maintain a reducing atmosphere in the fuel bed. The chemical flows out in molten form from the hearth. The combustibles in the gases rising from the fuel bed are burned, for which purpose additional preheated air is admitted above the fuel bed by means of the air nozzles 11, preferably downwardly inclined. Combustion under normal conditions of operation is usually completed at about a point marked 12. (Except in starting, the installation is self-sustaining, i. e., no extraneous fuel is required.)

The finned tubes 7 in effect constitute a continuous metallic wall lining the interior of the furnace and the inner face of which is exposed to radiant heat. The heat absorbed by the exposed surfaces is sufficient to lower the temperature of the gases leaving the top of the chamber A and entering the bottom of the chamber B to approximately 2000° F., well above the melting point of the chemicals. These two chambers open into one another at the level of the headers 13 and 13a into which the upper ends of the tubes 7, respectively constituting the side and front walls of the inner walls of the furnace are expanded.

Referring now to the boiler proper, this comprises a steam and water drum 14, a mud drum 15 and connecting banks of upright tubes 16 and 17, the tubes of the rows of each bank being staggered as indicated in Figure 2. The banks are baffled to provide vertical passes, the entrance to the first pass being below the steam and water drum 14. The front baffle is preferably formed by providing the front row of tubes 16a of the first bank with one inch fins 18. These tubes are three inches in diameter and are set on six inch centers, the gap between adjacent fins 18 being closed by the members 19. These tubes, the fins, and the closure members thus not only constitute a baffle for the first bank of tubes but also the rear wall of the chamber B.

Immediately in advance of the tubes 16a there is a vertically disposed superheater 20, suspended from above the boiler setting as indicated. The superheater tubes are one and five-eighths inch tubes, spaced on five and one-eighth inch centers in one direction and on six inch centers in a direction at right angles thereto. To guide and position the superheater unit at the rear, the tubes 16a are provided with lugs 21. In order to

guide and support the superheater unit at the front, a row of similar tubes 22 on six inch centers, extend upwardly and forwardly from the mud drum 15 and then vertically to the drum 23 which is connected to the steam and water drum 14 by the circulator tubes 24. The side walls of the chamber B are lined with one inch finned, three inch tubes 25 set on five and one-eighth inch centers, some of them connecting directly 5 with the drum 23 and the remainder with the headers 26 and 27, said tubes rising from the headers 13. The headers 26 and 27 are connected with the drum 23. The front wall for the chamber B is also lined with similar finned tubes 28 which rise from the headers 13a and are bent at the top to connect with the drum 23. Except for the two rear corners, it will be seen that the chamber B is lined with a substantially continuous metallic wall, the inner face of which is exposed to radiant heat.

The gases in rising from the furnace A at a temperature of about 2000° F. and through the chamber B flow in a direction parallel to the heat absorbing surfaces of the chamber, so that there 25 is no forcible impingement (except only on the inclined portions of the tubes—and the lower edges of the bends of the superheater tubes). Hence, the deposit thereon is powdery and friable in nature, and is easily removed. Nevertheless 30 the amount of heat absorbing surface in the chamber B is sufficient to lower the temperature of the gases and entrained particles to the point at which (approximately 1200° F., substantially below the melting point of the chemical) the 35 particles do not stick to the boiler tubes and build up, despite the forcible impingement of the gases and particles at the point where they flow across the tubes at right angles. Thus the deposit on the boiler tubes remains in easily removable form. Moreover, the self-sustaining operation of the unit is not interfered with despite the large amount of radiant heat surface; and the cost of installation is less than that of some other types now on the market of the same capacity.

It should here be added that the furnace shown has a horizontal depth of nine and one-half feet and a width of twenty feet, and that the chamber B is about the same size. From these and 45 other dimensions given the number of the various tubes, their length, and the surface presented, can be readily determined. The installation shown is capable of handling 600,000 pounds of dry solids in the liquor per twenty-four hour day.

Referring to Figure 4, I have there illustrated 50 an alternate form of water wall. The tubes are not finned and are practically in abutment with one another.

It is to be understood that a suitable downcomer means leads from the mud drum to the lower 60 headers of the water walls of the furnace.

No difficulty is encountered with deposit on the tubes 7, not only because of parallel flow of the flame and gas stream, but also because the temperature is sufficiently high to cause the deposit to melt and run down after having built up a slight amount.

The black liquor is normally fed to the furnace at a substantially uniform rate, determined by the desired capacity of the installation. In the installation shown, there is a superheater. Where superheated steam is not desired, the superheater may of course be substituted for by steam generating tubes. Insofar as the superheater is concerned, it is to be observed that the

upper loops lie outside the boiler setting, and therefore not subjected to gas flow.

I claim:

1. In a self-sustaining system for recovering chemical and generating steam from the black liquor of wood pulp mills, a smelter furnace into which the black liquor is sprayed, a chamber thereabove and successively arranged with respect thereto as to gas flow, a boiler successively arranged with respect to the chamber as to gas flow, closely spaced exposed tubes lining said furnace, closely spaced exposed tubes lining the walls of said chamber, said chamber having an opening at the upper part thereof through which the gases flow laterally into the tube bank of the boiler, and other tubes within the chamber and in advance of the boiler, all of said tubes being connected with the boiler and the amount of exposed surface of the said tubes being sufficient to lower the temperature of the gases before entering the boiler at all regular self-sustaining rates of operation to approximately 1200° F., and the tubes lining and in the chamber being so disposed that the gases have parallel flow therewith.

2. In a self-sustaining system for recovering chemical and generating steam from the black liquor of wood pulp mills, a smelter furnace into which the black liquor is sprayed, a chamber thereabove and successively arranged with respect thereto as to gas flow, a boiler successively arranged with respect to the chamber as to gas flow, closely spaced exposed tubes lining said furnace, closely spaced exposed tubes lining the walls of said chamber, said chamber having an opening at the upper part thereof through which the gases flow laterally into the tube bank of the boiler, and other tubes within the chamber and in advance of the boiler, all of said tubes being connected with the boiler and the amount of exposed surface of the said tubes being sufficient to lower the temperature of the gases before entering the boiler at all regular self-sustaining rates of operation to approximately 1200° F., and the tubes lining and in the chamber being so disposed that the gases have parallel flow therewith, the furnace and the chamber being of substantially the same dimension.

3. In a self-sustaining system for recovering chemical and generating steam from the black liquor of wood pulp mills, a smelter furnace into which the black liquor is sprayed, a chamber thereabove and successively arranged with respect thereto as to gas flow, a boiler successively arranged with respect to the chamber as to gas flow, closely spaced exposed tubes lining said furnace, closely spaced exposed tubes lining the walls of said chamber, said chamber having an opening at the upper part thereof through which the gases flow laterally into the tube bank of the

boiler, and other tubes within the chamber and in advance of the boiler, all of said tubes being connected with the boiler and the amount of exposed surface of the said tubes being sufficient to lower the temperature of the gases before entering the boiler at all regular self-sustaining rates of operation to approximately 1200° F., and the tubes lining and in the chamber being so disposed that the gases have parallel flow therewith, the furnace and the chamber being of substantially the same dimension, and the furnace being of such height that combustion is substantially completed therein.

4. In a self-sustaining system for recovering chemical and generating steam from the black liquor of wood pulp mills, a smelter furnace into which the black liquor is sprayed, a chamber thereabove and successively arranged with respect thereto as to gas flow, a boiler successively arranged with respect to the chamber as to gas flow, closely spaced exposed tubes lining said furnace, closely spaced exposed tubes lining the walls of said chamber, said chamber having an opening at the upper part thereof through which the gases flow laterally into the tube bank of the boiler and other tubes within the chamber and in advance of the boiler, all of said tubes being connected with the boiler and the amount of exposed surface of the tubes lining the furnace being sufficient to lower the temperature of the leaving gases to approximately 2000° F., and the amount of exposed surface of the tubes lining and within the chamber being sufficient to lower the temperature of the leaving gases, at all regular self-sustaining rates of operation to approximately 1200° F.

5. In a self-sustaining system for recovering chemical and generating steam from the black liquor of wood pulp mills, a smelter furnace into which the black liquor is sprayed, a chamber thereabove and successively arranged with respect thereto as to gas flow, a boiler successively arranged with respect to the chamber as to gas flow, closely spaced tubes lining said furnace, closely spaced tubes lining the walls of said chamber, said chamber having an opening at the upper part thereof through which the gases flow laterally into the tube bank of the boiler, and other tubes within the chamber and in advance of the boiler, all of said tubes being connected with the boiler, the amount of exposed surface of the said tubes being sufficient to lower the temperature of the gases before entering the boiler to approximately 1200° F. at all regular self-sustaining rates of operation and the tubes lining and in the chamber being so disposed that gases have parallel flow therewith.

ALEXANDER L. HAMM.
